CLAIM

The ornamental design for pivotable stand for an LCD screen, as shown and described.

DESCRIPTION

FIG. 1 is a perspective view of my new design;

FIG. 2 is a front elevational view thereof;

FIG. 3 is a rear elevational view thereof;

FIG. 4 is a top view thereof;

FIG. 5 is a bottom view thereof; and,

FIG. 6 is a right side view thereof, the left side being a mirror image.

The broken lines are for the purpose of illustrating form no part of the claimed design.
